SWITCHING SYSTEM

Edward E. Kleinschmidt, Chicago, Ill., assignor to
Teletype Corporation, Chicago, Ill., a corpora-
tion of Delaware

Application April 16, 1928, Serial No. 270,386

93 Claims. (Cl. 178—2)

My invention relates to telegraph systems in which a plurality of signaling lines extending from a plurality of outlying stations terminate at a central station. More particularly the invention relates to automatic switching apparatus for assigning a signaling line extending from a remote station to an idle telegraph set at the central station and for connecting a telegraph set at the central station with any one of the signaling lines for communication thereover.

In telegraph systems, the present day practice is to receive all the incoming messages for a large city at a central or main distributing station. This central station is connected to a plurality of scattered sub-stations located in various parts of the city by radial telegraph lines. The messages received at the central station are re-transmitted therefrom over one of these lines to the particular sub-station located nearest the final destination of the message. Similarly messages which originate at any of these outlying sub-stations are first transmitted to the central station and then re-transmitted to the remote destination. It is evident that in such systems the traffic consists wholly of messages between the central station and sub-station without direct communication between any two sub-stations.

In order to properly handle the signaling traffic a large number of telegraph sets must be located at the central station in preparation to receive messages from or send messages to each of these outlying stations. Inasmuch as it is desirable that any one of these sets may transmit to any one particular outlying sub-station, provision must be made for properly assigning the signaling line connected to the sub-station to any one particular telegraph set. It is equally necessary in the case of messages originating at the sub-station that the signaling line connection to the central station be properly connected to an idle telegraph set at the central station for receiving and re-transmitting the message to its remote destination. Heretofore this has been accomplished either by utilizing an independent telegraph set for each outlying station which is expensive, or by complicated switching apparatus.

Inasmuch as the signaling traffic handled at the central station at peak periods is heavy it is desirable to facilitate quick connections from the central station instruments to any substation and provide simple and reliable supervision of the sub-station line by the central station operator so as to avoid unnecessary attempts to seize busy lines. Since the signaling traffic varies from a peak load to a comparatively low load, a flexible

control of the destination of incoming calls at the central station whereby the total traffic may be concentrated upon a minimum number of operators during hours of low traffic and is distributed or separated into different classes of traffic during hours of heavy traffic.

It is accordingly an object of my invention to provide an automatic switching system in which a minimum amount of apparatus is employed to serve any given number of signaling systems, which facilitates quick automatic connection from a sub-station to a central station, provides simple and reliable supervision of sub-station lines by the central station operator, provides flexibility in the control of the destination of calls coming to the central station for concentrating the total traffic upon a small number of operators during hours of low traffic and properly distributing the traffic during hours of heavy traffic; in which complete control of all outlying station telegraph sets is obtained by the central station operator when once a connection is made to an outlying sub-station, in which a busy identification of all the lines in operation is provided at all times and in which the condition of a remote apparatus is at all times under supervision of the operator.

Further objects of my invention are such as together with the foregoing will appear in the following description of the preferred embodiment of the invention and are such as may be secured by the utilization of the combinations, sub-combinations and principles hereinafter set forth and as defined by the terms of the appended claims.

As shown in the drawings,

Figure 1 is a diagrammatic view of the circuits and apparatus employed in a preferred embodiment of the selecting system at the central station and at an outlying sub-station showing the interconnecting line and the automatic switching apparatus.

Figure 2 is a side elevational view of an embodiment of a preferred form of timing mechanism for rendering the sub-station telegraph apparatus in a non-operating condition at the end of a signaling period.

Figure 3 is a top plan view of the timing mechanism shown in Figure 2.

Figure 4 is an alternative mechanism for rendering a telegraph set non-operative.

Figures 5 to 7 are diagrammatic views of the alternative circuits and apparatus for locking the telegraph sets at the central station in a non-operating condition, and

Figure 8 is a diagrammatic embodiment of a preferred arrangement for audibly and visually

apprising an outlying station operator that connections have been completed to his set from the central station.

In Figure 1, a central station A is provided with a plurality of telegraph sets 1 and 2. It will be understood of course that these are merely illustrative and that any number of such apparatus may be located at the central station. In the present illustration certain of the sets at the central station, such as 1, are allotted for outgoing messages and the others, such as 2, for incoming messages.

The transmitting apparatus 1 is connected by means of conductors 3 and 4 to automatic switching equipment 5 individual thereto. It will be understood that similar switching equipment is provided for each printing apparatus such as 1 assigned to outgoing signals although if desired the same automatic switch may be common to a plurality of sets. The automatic switching equipment 5 controls rotary and vertically moving wipers 6 and 7 which move over a bank of contacts 8 and 9 respectively in a manner to be described in detail hereinafter for connecting the set 1 through conductors 11 to any one of a plurality of signaling lines such as 12 connected to telegraph apparatus 13 at the outlying station B. The automatic switching equipment here diagrammatically shown is of the well known type disclosed in Aitken's "Automatic Telephony". Conductor 12 individual to outlying station B is also connected by means of conductor 14 to switching equipment 15 which in a manner to be described in detail hereinafter when operated from the outlying station B will connect the signaling line 12 extending to the outlying station from conductor 14 to any idle receiving telegraph set 2. A bank of lamps 16 comprising lamps individual to each signaling line 12 are connected with both automatic switching apparatus 5 and 15 and indicate at all times which of the lines extending to the remote or outlying sub-stations are busy. The operators at the central station by observing the lamps avoid useless effort in attempting to connect to a busy line.

The telegraph apparatus 1 comprises a printer magnet 18 and transmitter 19 of the well known type such as described in the patents to Krum #1,595,472 issued August 10, 1926 and to Klein-schmidt #1,567,292 issued December 29, 1925. A lamp 20 is connected in series with this telegraph set for indicating to the operator by its flashing when communication is being carried on by this set with some outlying station. The current for such signaling is provided by battery 21 connected to ground at 22. A busy alarm 23 is connected in multiple with magnet 18 and operates in a manner to be described for apprising the operator that the line he has picked is busy. Device 23 is connected through condenser 24 to ground so that direct currents are kept out and only alternating currents to which device 23 responds pass through. A motor 26 connected to battery 27 is connected over conductor 28 to switch 29 controlled by key 31. The motor 26, it will be understood in operation controls the printing apparatus in accordance with the operation of the magnet 18 responsive to signaling impulses. Normally motor 26, magnet 18, and transmitter 19 are connected to each other through a contact 32 and inasmuch as batteries 21 and 27 are connected in opposing relations, no current flows and the apparatus is in a non-operating condition. The key 31 which is of the snap-operating type has three positions, a mid

non-operating position, a lower position, as shown, and an upper position. In addition to switch 29 a switch 33 is closed when the key is in its lower position and switches 34 to 36 are closed in the upper position. Of these, switch 5 29 controls the connection of the signaling line 4 to the printing apparatus in a manner to be described in detail hereinafter and switch 33 controls the energizing circuit for motor 26 and a temporary energizing circuit for printer magnet 18. By this arrangement when switch 33 is closed in preparation for signaling operations, motor 26 is started into rotation. Simultaneously magnet 18 is energized and since the magnet is energized during a normal non-operating or 15 stop period, no operation occurs at this time although the motor 26 is rotating. A similar circuit for the motor 26 is controlled over switch 34 when the key 31 is in its upper position.

With key 31 in its lower position, set 1 is connected for outgoing messages only. With key 31 in its upper position, the set 1 operates for incoming messages. Switches 34 to 36 complete circuits for the set 1 from automatic switches 15 to condition the set for incoming signals, in the 25 manner to be described in detail hereinafter. A relay 41 which is normally energized controls the final connection of the main signaling circuit to the telegraph set over armature 42. Relay 41 is normally energized and connects the 30 main conductor 4 to trip magnet 43 which energizes in response to the first impulse received to open switch 44 controlling the circuit of relay 41. Switch 44 is also controlled by a timing mechanism 45 to be described in detail herein- 35 after for reclosing the circuit of relay 41 an interval after signaling has ceased.

A dial 46 connected in line 4 is also provided at the central station individual to each set to enable the operator thereat to transmit a predetermined code to the automatic switch 5 to seize a predetermined signaling line extending to an outlying station. Dial 46 is of the usual type employed in automatic telephony. Its shunt switch 47 temporarily maintains a circuit closed to the local telegraph set while the dial opens and closes line 4 for signaling.

In telephone practice the opening and closing of a line for transmitting the signals to operate the automatic switching apparatus removes current from the telephone receiver and transmitter. In telephone operation, this is endured. When, however, as in the case of telegraphy, it is desired to maintain the printing apparatus in a normally closed circuit during non-operating 55 periods, provision must be made for maintaining the apparatus closed during the signaling period inasmuch as an open signal is a start operation for the apparatus which is accordingly started in the event that the printer circuit is opened while 60 the automatic switching operations are taking place. This is clearly undesirable. In the present case such operations are avoided by the contact 47 on the dial 46 to maintain the circuit to the telegraph apparatus closed. A switch 48 65 connected in pilot conductor 3 varies the resistance in this line as it opens and closes for varying the luminosity of a lamp connected therein whereby the operator is apprised of the signaling line to which he is connected. Switch 49 opens 70 this circuit for restoring the apparatus to normal. These operations will be described in detail hereinafter.

As described above, the automatic switching apparatus 5 is connected to the telegraph set 1 75

over conductors 3 and 4. Automatic switching apparatus 5 comprises a bank of contacts 8 and 9 over which the wipers 6 and 7 move in a vertical and rotary motion under control of the vertical stepping magnet 51 and rotary magnet 52 respectively. This apparatus is of well known construction in the telephone art as described in Aitken referred to above and is here illustrated diagrammatically. An off normal switch 53 is arranged to maintain its contacts 54 and 55 normally disengaged and contact 56 is engaged while the switch wipers 6 and 7 are in their normal non-operating position. Upon the first energization of the vertical stepping magnet 51, contact 56 opens and contacts 54 and 55 close.

Receiving relay 57 is connected in the line circuit and responds to impulses from the dial 46 for operating the vertical and rotary stepping magnets 51 and 52. A slow to operate relay 58 is energized upon the first operation of the receiving relay 57 for connecting the armature 59 to the windings of vertical and rotary stepping magnets at its armature 62 and at armature 63 to open the circuit of restoring magnet 64. As will appear hereinafter during the operation of switch 5, relay 58 remains energized during the operation of the automatic switching apparatus and no circuit can be completed for magnet 64.

A slow to operate relay 65 is energized in response to the first impulse received at switch 5 and switches these impulses to the vertical stepping magnet 51 over armature 66. At the end of the first group of impulses relay 65 de-energizes to switch the signal to rotary stepping magnet 52. In the event that the line which is selected is busy, this relay will remain energized thereafter and will connect the alternating current generator 68 to the line 4 at armature 69 for operating the busy alarm device 23 at apparatus 1. If the line seized by the automatic switching apparatus is idle, relay 67 de-energizes to prepare a circuit for relay 75 at armature 76. Relay 75 energizes when the line seized is idle and completes the switching operation at armature 17. At armature 78 the pilot circuit 3 is switched to pilot line 79, individual to line 12 and outlying sub-station B. At armature 81 the circuit for restoring magnet 64 is opened preventing energization of this magnet during signaling operations and at armature 82 the circuits for rotary magnet 52 and slow release relay 67 are opened. As will now be clear the switching apparatus 5 operates for outgoing signals to select the particular line extending to the outlying station B with which the signaling is desired.

A different form of connector switch 15 is employed to operate in response to incoming signals for connecting an outlying station to an idle local set. Receiving relay 91 is normally energized and connected over its armature 92 and its front contact and the back contact and armature 93 to conductor 14 connected through resistance 94 to signaling line 12, extending to the outlying station B individual to automatic switch 15. As will be described hereinafter, relay 91 operates in response to the first operation at station B for connecting slow to operate relay 95 in circuit with the line 14. Thereafter this relay operates to energize the stepping magnet 96 over armature 97. Stepping magnet 96 controls the wipers 98 to 100 of switches 101 to 103 respectively. Each of these switches comprise in addition to their individual wipers, a set of bank contacts about which the wipers successively engage in a manner which is well understood in the telephone art

and is described in detail in Aitken referred to above. Relay 104 controlled over armature 105 connects the local set to the signaling line over armature 93, connects the pilot circuit to the set at armature 106, and prepares a restoring circuit at armature 107 as will be described in detail hereinafter.

Switch 101 controls the restoring circuits, switch 102 tests the sets to determine whether they are busy, and switch 103 completes an energizing circuit to the set selected, as will be described hereinafter.

One such set 2 is illustrated in Figure 1. As in the case of set 1 it comprises a receiving magnet 111 and transmitter 112 connected in series 15 with a lamp 113 and battery 114. This set is controlled by a motor 115 connected in circuit with battery 116. The telegraph set and motor are normally in non-operating condition, their batteries being connected in opposition at armature contact 117. Relay 118 controlling contact 119 is energized over a circuit including switch 119 controlled by timing mechanism 120 similar to mechanism 45. Normally the line 121 is connected over armature 122 to trip magnet 123' 25 controlling switch 119. When relay 118 de-energizes this circuit is switched to include magnet 111 and transmitter 112. At armature 123 the pilot line 124 is connected to switches 125 and 126. Switch 125 varies the resistance in the pilot 30 circuit to apprise the operator of the outgoing line to which he is connected and switch 126 opens this circuit to restore the apparatus to normal as will be described in detail hereinafter.

The extension of pilot line 124 is connected to 35 a lamp 127 individual to the line 12 extending to outlying station B. The illumination of this lamp 127 provides a continual indication of the lines which are busy.

While the signaling traffic is heavy, it is desirable that independent telegraph sets be employed for the outgoing signals and for the incoming signals. When, however, the traffic becomes light, it is preferable to operate the same sets for both classes of signaling. This is accomplished by switch member 131 controlling switches 132 to 134. In the position shown in the drawings, the telegraph equipment 2 is connected to respond to incoming signals. When, however, the load becomes comparatively light 50 and it becomes more desirable to switch the incoming signals to telegraph apparatus 1, switches 132 to 134 are moved to their lowermost position.

At the remote station substantially similar apparatus is employed. The signaling line 12 is normally connected over armature 141 to the release magnet 142. The magnet 142 controls a switch 143 through which the energizing circuit for relay 144 is completed. At its armature 145, relay 144 controls the energizing circuit for the motor 146 and at its armature 141 controls the circuit for the releasing magnet 142. Switch 143 it will be noted, is controlled by timing device 147 which is released by the releasing magnet 142. When a current of sufficient strength is received 65 the magnet 142 responds thereto to open the switch 143 opening the circuit of the relay 144 which upon deenergization closes the circuit for the motor 146 at armature 145 and at armature 141 completes the circuit for the receiving magnet 148 and the transmitter 149 of telegraph set 70 150. A key 151 is connected in series with this circuit to enable control of the circuit by the operator. The apparatus and its operation will now be more clear from the detailed descriptions of 75

the operations which occur when the operator at the central station wishes to communicate with any one of the outlying stations and when an operator at an outlying station desires to communicate with the central station. It will be first assumed that the operator at telegraph set 5 desires to communicate with the outlying station B.

Normally the motor 146 at the outlying station 10 is in non-operating condition inasmuch as its circuit is open at armature 145 due to the energization of relay 144 over a circuit including the switch 143. Although an energizing circuit is at this time completed for the magnet 142 from 15 ground through the key 153, the winding of the magnet 142 armature 141 and its front contact over conductor 12, resistance 94, conductor 14, armature 93 and its back contact, armature 92 and its front contact, and through the winding of 20 relay 91 to battery and ground, the energy transmitted over this circuit from the battery, because of the arbitrarily high resistance of the winding of relay 91 is insufficient to operate the magnet 142 and accordingly the switch 143 remains in the 25 position shown. The receiving magnet 148 and the transmitter 149 are therefore normally disconnected from the signaling line at armature 141.

At the central station trip magnet 43 is normally open circuited at the switch 29 which is in its open position while the switch arm 31 is in its neutral non-operative or mid-position. Relay 41 is energized over a circuit including the switch 44 in its closed position and prepares a circuit for 30 the trip magnet 43 over its armature 42 and its front contact. The motor 26 is at this time open circuited at the switches 42 and 33 which are in open position and similarly the receiving printer magnet 18 and transmitter 19 are open at the 40 same contacts.

In order to start operations, the operator at set 45 will move his switch arm 31 to the position shown in Figure 1. A circuit is thereupon completed from ground over switch 33, motor 26 and battery 27 to ground. Motor 26 starts rotating and prepares the printer set for operation. Simultaneously an energizing circuit is completed for the magnet 18 from ground through battery 21, pilot lamp 20, transmitter contact 19, 50 magnet 18, make before break contact 32, resistance 161 and ground over the switch 33. Inasmuch as energization of magnet 18 is the stop condition of the printer set, it will now remain in its non-operating condition with the motor 26 55 rotating.

A circuit is also completed for the trip magnet 43 from ground through battery, winding of the trip magnet 43, front contact and armature 42, over the conductor 162, switch 29 and its lower 60 contact, through the contact of the code transmitter 46, conductor 4, armature 77 and its back contact, conductor 163 and through the winding of the automatic switch operating relay 57 to ground. This impulse from the battery transmits sufficient current to operate the trip magnet 43 and relay 57.

Energization of the trip magnet 43 operates the switch 44 to open the circuit of the relay 41. Relay 41 upon deenergization opens the circuit of trip magnet 43 at armature 42 which has now moved to engage its back contact and as a result the circuit of the magnet 18 and transmitter 19 is switched from the switch 33 to conductor 162, switch 29 and the signaling line 4. Inasmuch as 70 this circuit is closed through relay 57 the magnet

18 remains energized during this switching operation. It will be noted that this circuit is completed by the make before break armature 42 before the original circuit for magnet 18 is opened so that no break in the circuit of this magnet 5 occurs.

At the automatic apparatus 5, the relay 57 energizes as a result of the circuit traced above therethrough to operate its armature 59 into engagement with its front contact and as a result 10 an obvious energizing circuit is completed for the slow to operate relay 58. The energization of the slow to operate relay 58 prepares an energizing circuit at armature 62 and its front contact, off normal switch 56 over conductor 164, winding of 15 the slow to operate relay 65 through the vertical stepping magnet 51 and battery to ground. The operator will now operate his dial 46 to transmit a predetermined combination of impulses to the automatic switch 5. 20

As the impulses are transmitted, the relay 57 of the automatic switch 5 deenergizes and reenergizes. Upon the first deenergization of the relay 57, the energizing circuit for the vertical stepping magnet 51 is completed over the armature 59 and its back contact and armature 62 and its front contact and over the circuit traced above through the relay 65 and magnet 51 in series to battery and ground. 25

Relay 65 energizes and prepares a locking circuit for itself at armature 66 and vertical stepping magnet 51 is energized thus mechanically stepping wipers 6 and 7 to their first operating level. Although the circuit for relay 58 is opened at this time, it remains energized because of its slow to 30 deenergize characteristic and relay 57 is again energized by the succeeding impulse before relay 58 can deenergize. 35

Upon energization of relay 57, in response to the next impulse, the vertical magnet 51 deenergizes. It will be understood by those skilled in the art that each contact on the switch banks such as contact 165 is connected to the individual line extending to an outlying station such as B, and similarly a contact such as 166 is connected over pilot conductor 79 to an individual lamp such as 127. 40

This first operation of the automatic switch closes contacts 54 and 55 of the off normal switch and opens contact 56 in a manner well understood by those skilled in the art. Opening of contact 56 opens the original circuit for slow release of relay 65 but its locking circuit is now extended through unnumbered contact in the off-normal switch and front contact and armature 55 62. When now the relay 57 is deenergized at the end of this impulse, relay 65 is locked over the back contact and armature 59 and vertical stepping magnet is energized a second time. 55

It will be assumed that in the present case the 60 operator transmits three impulses to step the wipers 6 and 7 vertically to the third level in this case shown uppermost. Thereafter a pause occurs while the dial 46 is being reset during which the relay 57 remains energized. During the 65 transmission of these impulses in closing the circuit of the vertical stepping magnet 51 the slow to operate relay 65 remained energized over a circuit in series with the vertical stepping magnet, front contact and armature 66, the now 70 closed off normal switch contact unnumbered, front contact and armature 62 and the back contact and armature 59 to ground following each deenergization of the relay 57. The intervals when relay 57 is energized are too short to per- 75

mit relay 65 to deenergize. At this time, however, the line is maintained closed while the dial 46 is being reset and the relay 57 remains energized for a sufficient period to permit the 5 slow to operate relay 65 to deenergize and armature 66 moves to engage its back contact. The original energizing circuit for the slow to operate relay 65 is now opened at off normal contact 58 so that this relay can no longer energize. 10 When now the next series of impulses are transmitted due to the opening and closing of the dial 46, the circuit from the armature 59 is switched from the vertical stepping magnet 51 to the rotary magnet 52, the circuit being complete 15 from ground over armature 59 and its back contact, armature 62 and its front contact, the closed contact unnumbered of the off normal switch 53, armature 66 and its back contact and armature 82 and its back contact, through the 20 winding of the rotary stepping magnet 52 to battery and ground. The rotary magnet 52 as it is now energized and deenergized with each deenergization and reenergization of the relay 57 will move the wipers 6 and 7 in a rotary direction to the first and then to the succeeding contacts. In the present case it will be assumed 25 that two such impulses are transmitted and the switch wiper 7 ultimately rests on the contact 165 and the switch wiper 6 rests on the contact 30 166.

In multiple with the rotary stepping magnet 52, an energizing circuit is also completed for the relay 67 from ground through battery, the lower winding of the relay 67, back contact and armature 82 over the armature 66 switch contact unnumbered and armatures 62 and 59 to ground. Upon the first energization of the relay 67, a 35 circuit is prepared for the busy ringer generator 68 at armature 69 and its front contact. At 40 armature 76, a locking circuit is prepared for the relay 67, through its upper winding armature 76 and the wiper 6. At the end of the second group of impulses, a pause again occurs of sufficient length to permit the slow relay 67 to 45 deenergize while relay 57 is held energized causing its armatures 76 and 69 to move to their back position. At this time the switch wiper 6 is in engagement with its contact 166. Should the selected line be idle the circuit from battery 50 through relay 67 to wiper 6 meets a circuit from battery through lamp 127 to contact 166 and wiper 6 and also a circuit from battery through the driving magnet 96, contact 170, relay 104 and wires 126' and 79 to contact 166 and wiper 6 55 and current will not flow. The slow relay 67 therefor deenergizes and a circuit is now completed for the upper winding of relay 75 from ground through the upper winding of relay 75, back contact and armature 76 over the brush 6 in engagement with contact 166, conductor 19, 60 and dividing through the pilot lamp 127 to battery and ground, and also through wire 126', relay 104, and magnet 96 to battery and ground. As a result of this circuit relay 75 is energized 65 and the lamp 127 is illuminated indicating to the operator at set 1 that he has seized the line with which the lamp 127 is associated insuring correct connection. A locking circuit is now completed for the relay 75 through its lower 70 winding, from ground through battery the lower winding of the relay 75, front contact and armature 81 over the pilot conductor 3 and through the contacts of the switches 49 and 48 to ground. The operation of the armature 81 not only locks 75 the relay 75 in its energized position but also

opens the circuit for the releasing relay 64 at the back contact, opens a further point in the circuits for the slow to operate relay 67 and the rotary stepping magnet 52 at armature 82 and opens the circuit of the relay 57 at armature 77. At the make or break contact of armature 78 the pilot line 3 is connected over wiper 6 and contact 166 directly to lamp 127 over conductor 79. The armature 77 transfers the circuit for the signaling line 4 from relay 57 controlling the 10 automatic switch 5, to the signaling line 11 extending to the outlying station.

In the event that the signaling line 11 which is engaged by the brushes 6 and 7 is busy, that is connected to some other set at the central 15 station with which communication is being carried on, the conductor is grounded in a manner to be described in detail hereinafter, and when seized by automatic switch 5, an energizing circuit is completed. The relay 67 therefore remains 20 energized after the brush 6 engages the contact 166. This circuit is completed from ground through battery, upper winding of the relay 67 front contact and armature 76, make before break contact of the relay 75, at armature 78 brush 6 25 in engagement with the contact 166, conductor 79 to ground as will be described. The relay 67 when thus maintained energized, maintains the energizing circuit for the relay 75 open at armature 76 to prevent this relay from energizing and 30 at armature 69 closes the circuit for the generator 68 over armature 69 and its front contact, conductor 4 through switch 29, conductor 162 armature 42 in engagement with its back contact, and through the busy alarm 23 to ground. The dispatcher is then apprised by this alarm signal that connection has been made with a busy line and will therefore restore his apparatus until the line 35 becomes idle for use.

It will be noted that a circuit in multiple with 40 the lamp 127 is completed for the winding of relay 104 from ground on conductor 78 as traced above over conductor 126' through the winding of relay 104, and the winding of the stepping magnet 96 45 in a de-energized condition to battery and ground. The magnet 96 is not energized over this circuit as the current from the battery is insufficient to operate it. Relay 104 is however, energized and operates its armatures to break their back contacts. The armatures of relay 104 and 95 have a 50 mechanical connection so that if relay 95 is not energized armature 106 and 93 cannot engage their front contacts although armature 107 can and maintains relay 91 energized. It will be noted that as the contact of dial 46 opens the line circuit 4, a switch 47 completes an energizing circuit for the magnet 18 from ground through the switch 47 in engagement with its contact, switch 29, armature 42, and its back contact through the receiving magnet 18, the transmitter 19 and battery 21 to ground. This maintains the magnet 18 55 energized during the period while the dial 46 transmits the code for operating the automatic switch in order to prevent operation of the magnet 18 at this time.

It will be assumed that the line 12 has been seized, that the relay 67 has completed an energizing circuit for relay 75 which thereupon locks itself. A circuit is now completed from the telegraph set at the central station to the telegraph apparatus at the remote station, the circuit being completed from ground through battery 21, lamp 20 transmitter 19, magnet 18, make before break contact in engagement with the armature 42, conductor 162, switch 29 in its lowest position, con- 70 75

tact of the dial 46 conductor 4 armature 11 in engagement with its front contact, brush 7 in engagement with the contact 165, conductor 11, through the resistance 94, conductor 12, front contact and armature 141 the winding of the release magnet 142 and through the key 153 to ground. Magnet 142 is energized over this circuit and operates the switch 143 to open the energizing circuit for the relay 144. The de-energization of the relay 144 completes an obvious energizing circuit for the motor 146 at armature 145 and its back contact. At armature 141 a make before break circuit is completed connecting the telegraph magnet 148 and transmitter 149 in circuit with the conductor 12 and in series with the magnet 18 and transmitter 19 at the central station. The telegraph transmitter and receiver at the central and remote station are now connected in series, the magnets being energized for a stop condition. Lamp 127 is at this time illuminated over a circuit traced above to indicate the line seized. Since however, a number of lines may be busy, it is desirable for the operator to check the particular line with which he is connected. This is accomplished by operating key 48 to change the resistance in the pilot circuit including the lamp 127. If this lamp is dimmed by this operation the dispatcher will thus be apprised of the line with which he is connected. Transmitter 19 is now operated in accordance with the code to be transmitted and the magnet 148 at the outlying station B operates in response to this code to control the printer thereat. It will be observed that during this period, the operator at the central station has full control of the signaling line at switch 49 and may continue communication with the outlying station as long as desired.

When communication is no longer desired the operator at the central station by operating his key 49 opens the circuit of conductor 3 whereupon the locking circuit for the relay 75 traced above is opened and this relay deenergizes. Upon the deenergization of relay 75, an energizing circuit is completed for the restoring magnet 64 from ground through battery, the winding of the restoring magnet 64, closed contact 54 of the off normal switch 53, armature 63 and its back contact, back contact and armature 81, conductor 3 and through switches 49 and 48 to ground. Restoring relay 64 when energized, functions to return the wipers 6 and 7 to their normal non-operative condition. An interval of time after signaling ceases, timing mechanism operate switches 44 and 143 to restore their respective sets to non-operating positions shown.

In the event that the operator at the outlying station B desires to communicate with the central station, the apparatus being in normal non-operating condition, he will operate briefly the key 153, opening briefly the energizing circuit of the relay 142 at the outlying station and the relay 91 at the central station. Deenergization of the relay 91 releases its armature 92 which closes a circuit for the relay 95 from ground and battery through the winding of the relay 95, back contact and armature 92, back contact and armature 93, wire 14, resistance 94, wire 12, front contact and armature 141, winding of magnet 142 and key 153 to ground. Owing to the arbitrarily high resistance of the winding of relay 95, the current in this circuit is insufficient to operate the magnet 142, but the relay 95 responds. Energization of relay 95 of the automatic switch 15 at the central station completes an energizing circuit for the stepping magnet 96 from ground

through battery to the winding of the stepping magnet 96 its own back contact, armature 97, and its front contact, back contact and armature 106 and through the brush wiper 99 to ground. At armature 105, the conductor 126' is now grounded. If thereafter the connector switch 5 attempts to seize this line as described above the ground will prevent energization of the relay 75 and will maintain relay 67 energized as has been described above so that the operator 10 at the central station is apprised that the line is now busy.

The winding of relay 104 has its lower terminal now connected through armature 105 to ground and has its upper terminal now connected 15 through armature 97 (operated) armature 106 and wiper 99 to ground. These two ground connections short-circuit the relay 104 which therefore remains deenergized at this time. The current flow in magnet 96 being however, directly 20 grounded at wiper 99 as traced above this stepping magnet is energized to operate its pawl for stepping the switches from their normal contact to their second contact and at the same time opens its own energizing circuit at its contact 25 170. The stepping magnet 96 is thereupon deenergized to again close its circuit over the circuit traced above, except that at this time the brush 99 being in engagement with its second contact, the circuit extends over conductor 124 30 switch 133 in its upper position, to armature 123 and its back contact, if the relay 118 is deenergized and ground over switches 125 and 126. In the present case, the relay 118 being energized, this indicates that the apparatus 2 is in 35 a non-operating condition, that is, that it is in condition to be seized by the operator at the remote station. Since the circuit for this stepping magnet 96 is opened at armature 123 the only circuit through stepping magnet 96 is completed from ground through battery through the winding of the stepping magnet 96, its back contact 170, winding of the relay 104 and armature 105 and its front contact, to ground. The current flow is insufficient to operate the stepping 45 magnet 96 but sufficient to energize the relay 104. Upon energization of the relay 104 a circuit is completed from the apparatus at the remote station to the central station from ground through key 153, trip magnet 142, armature 141, line wire 50 12, equalizing resistance 94, wire 14, armature 93, brush 100, wire 121, switch 134, armature 122, trip magnet 123' and battery to ground.

The two trip magnets 142 and 123' operate and open the two time-switches 143 and 119. 55 The opening of the switch 143 deenergizes the relay 144 and permits the armature 145 to start the motor 146 by an obvious circuit. The motor 146 of the calling station thus is started by re- 60 vertive control of the called station, and the calling station has remained non-operative until a time subsequent to its connection to the called station.

The deenergization of the relay 144 also permits the armature 141 to connect the line 12 65 through the printer-magnet 148, the sender 149 and the switch 151 to ground, and to disconnect the trip magnet 142 from the line 12. Simultaneously the deenergization of the relay 118 permits the armature 122 to connect the wire 121 70 through the printer-magnet 111, the sender 112, the lamp 113 and the battery 114 to earth, and to disconnect the trip magnet 123' from the wire 121.

The energization of the relay 104 has operated 75

its three armatures 107, 93 and 106. The operation of the armature 93 has caused the operation of the trip magnets 142 and 123' as described. The operation of the armature 107 reenergizes the relay 91 over an obvious circuit, thus operating its armature 92 and opening the circuit of the winding of relay 95 which in turn will release its armature 105 to open the circuit over which the relay 104 was energized, but the armature 105 of the relay 95 is slow-to-release and before it breaks its contact the relay 118 will have provided a holding circuit for the relay 104, as follows: From earth and battery through magnet 96, contact 170, winding and front contact and armature 106 of relay 104, brush 99, wire 124, switch 133, armature 123, switch 125 and switch 126 to ground. This circuit maintains the connection thus set up and the connection may be released only by the manual operation of the key 126.

The simultaneous operation of the relays 144 and 118 has completed the circuit between the telegraph set at the central station and the telegraph set at the remote station, from ground through battery 114, lamp 113, transmitter contact 112, magnet 111 back contact and armature 122, switch 134, conductor 121, second contact and wiper 100, front contact and armature 93, conductor 14, resistance 94, conductor 12, make before break contact 141, magnet 148, transmitter contact 149 and switch 151 to ground. Signaling communication may now be carried on between these two stations.

If the switches upon engagement with their second contact complete a circuit to a telegraph set such as 2 which is in operative condition at the time; that is, is busy communicating with some other station, relay 118 would be deenergized whereupon a circuit is completed from the earth of key 126 over conductor 124, second contact and wiper 102, armature 106 and its back contact, front contact and armature 97, to the stepping magnet 96, and battery. Relay 104 would not be energized as ground on conductor 124 shunts the winding of relay 104. Magnet 96 is thereupon again energized to step the wipers to the succeeding contact connected to the next telegraph set. In this manner the wipers 99 continue to operate from contact to contact until switch contacts are reached at which the apparatus is not in operated condition in which case stepping magnet 96 and relay 104 receive current in series whereupon the latter operates and connects the signaling line 14 through to the particular set with which the switch wipers are connected.

Upon energization of the relay 104, it will be observed that a multiple circuit is completed from ground on conductor 124 over armature 106 and its front contact, conductor 126', to the lamp 127 and battery to ground, apprising the operator at the central station that the signaling line to remote outlying station B is busy at this time.

In the event that all of the central station apparatus is busy the wipers move from contact to contact until they reach their twenty-fourth contact or their next to last contact at which point a circuit is completed from the generator 68 over this contact, wiper 100, conductor 14, to the alarm device 171 at the outlying station apprising the operator that all the equipment is busy whereupon he will restore the apparatus for later operation.

The wiper 100 pauses briefly upon the busy-

signal contact point to prolong the signal upon the device 171.

The means for stopping briefly is the vacant point unnumbered on switch 102. As shown, in normal condition the wiper 99 is in connection 5 with earth. When the search starts, relay 95 is charged, relay 104 is uncharged. Busy wires 124, keep wiper 99 connected to earth when all printer lines are busy, until wiper 99 reaches its last point before normal; on this point there is no 10 wire 124, no earth, no busy test, no shunt for relay 104 and relay 104 operates, stops the switches 102 (99) and 103 (100) and sends current for the audible-signal device 171 at station B. Relay 104 has opened the circuit of relay 95 15 and during the delay of the slow-to-release relay 95 the audible-signal condition continues. Relay 95 now releases armature 105, closing circuit for operating the magnet 96 through armature 97 and brush 98 to earth at 107, and the switches 20 102, 103 pass to normal position, interrupting the audible signal.

It will be observed that even in the case of incoming signals, the operator at the central station retains complete control of the signaling 25 operations and may signal for extra information. In order to be assured of the particular outlying station with which he is in communication he needs only to operate his switch 125 which will cause the lamp 127 to dim and brighten as 30 the switch is operated apprising him thus of the particular line with which he is connected. As soon as the operator at the central station is through communicating he will operate his switch 126 opening the locking circuit for the 35 relay 104 traced above. Relay 104 thereupon deenergizes and at armature 93 connects the line 14 through to the relay 91. An energizing circuit is now completed for stepping magnet 96 from ground through battery, winding of the stepping 40 magnet 96 and its own contact 170, armature 97 and its back contact, wiper 98 and the contact with which it is in engagement over the back contact and armature 107 to ground. Stepping magnet 96 steps the wipers 99 to 100 to their 45 succeeding contact, and opens its own circuit and upon deenergization again completes its own circuit. This operation continues until the wipers are restored to their normal position shown. A further result of the operation of armature 93 50 to its back contact is to open the energizing circuit for the telegraph apparatus at the central station. The timing mechanism 120 and 147 operate after an interval of time to close the circuits of relays 118 and 144 respectively 55 which in turn open the energizing circuits of the motor 146 and connect magnets 123' and 142 in preparation for operating switches 119 and 143.

In the above description of the apparatus it 60 will be observed that the telegraph apparatus at 1 operates for outgoing signals and telegraph apparatus 2 operates in accordance with incoming signals. During part of the operating period however, the traffic becomes so light that it can 65 all be carried by just one set of apparatus. In such a case the switch 131 is operated, and switches 133-134 are moved from their upper to their lower positions. Switch 133 transfers the connections of pilot conductor 124 from the apparatus at 2 to the apparatus at 1 over conductor 172 while the switch 134 transfers the circuit over conductor 121 from set 2 to set 1 over conductor 173. Set 1 is then in condition to both 70 send out the signals and receive incoming signals. 75

Switch 132 moving from its contact opens the circuit for the motor 115 rendering the telegraph set 2 in a non-operating condition.

A mechanical form of time release is shown in

- 5 Figures 2 and 3. A time gear 180 is driven through worm gear 181 mounted on and rotatable with motor shaft 182 by the motor 183. A worm follower 184 carried on the worm 185 and rotatable with shaft 186 is normally drawn away from 10 the contact 187 by the spring 188 and is propelled towards the contact 187 by engagement of the follower 184 with the worm 185.

If desired a complete mechanical control may be utilized. The motor 183 through meshing gears 15 195 and 196 and clutch 198 drives the cam 197 which at every revolution engages the follower 184 and lifts the follower 184 from the worm 185. The printer clutch 198 engages only while printing operations are taking place. As soon as the printing 20 ceases, the clutch disengages and the follower 184 is permitted to be operated by the worm 185 to engage the contact 187. It will be understood that contact 187 is the equivalent of contacts 119, 143 and 44 in Figure 1. When the trip magnet 190 is energized, the armature 191 rocks upon 25 its pivot and engages the follower-frame 192 thus rocking the frame 192 about its pivot 193 against the tension of the spring 194. The rocking of the frame 192 lifts the worm-follower 184 free from the worm 185 thus permitting the spring 188 to move the follower 184 to release the contacts 187 to permit the contacts to open. The trip magnet 190 of Figure 2 appears in Figure 1 at 43, 123' and 142.

30 35 In order to apprise the station B operator that signals are being received, a special code bar 201 Figure 8, is operated by the first code transmitted from the central station to the outlying station selected. Upon the operation of the bar 201, in 40 the manner described in the above referred to patent, the pivoted operating lever 202 is rocked about its pivot 203, as the bar 201 engages the horizontal pin 204 extending from lever 202. Lever 202 is rocked and operates the visual indicator 205 through a slot 206 in the frame 207 as shown in the dotted lines. This gives a visual indication to the operator at the outlying station that connection has been completed for communication from the central station. The operator 45 thereafter restores the visual indicator 205 to its position. Simultaneously the hammer 208 is released at the latch 208' and as the cam 209 rotates the hammer 208 operates against the bell 210 to give an audible indication to the operator. 50 55 Upon the complete rotation of the cam 209 the hammer 208 is again operated to its latched position shown.

In Figures 4-7 modified arrangements are disclosed. As shown in Fig. 5 relay 215 of the slow to operate type maintains its armature 216 in engaged position with its contact during the period while the signaling line such as line 12 Figure 1 is closed through telegraph apparatus at the outlying station. The telegraph current is of sufficient intensity to maintain armature 216 in engagement with its point contact which in turn closes an energizing circuit for the relay 217. Relay 217 upon energization closes an energizing circuit for the motor 218 at armature 219 and its front contact and the motor and telegraph set will accordingly be in operation while telegraph signals are being received. The relay 215 however, is marginal in character and when communication ceases and the line closes for the

supervisory currents only, it is of insufficient intensity to maintain the armature 216 in engagement with its contact, and armature 216 after an interval of time will drop to its back position. Inasmuch as the relay 215 is slow to operate and 5 slow to release the armature 216 will not drop to its back position during the intervals between the signaling periods as these are too short to sufficiently deenergize relay 215. When however, a sufficient period of time elapses, relay 215 de- 10 energizes and armature 216 drops to its back contact, opening the circuit of the relay 217 which in turn opens the energizing circuit of the motor 218. A bypass circuit is completed around the transmitter contact 221 at armature 220 so that 15 apparatus including the magnet 222 is rendered non-operative thereafter. The switch 223 corresponding to 153 in Fig. 1 is rendered non-operative during the signaling period. The busy signal device 224 as usual is connected through condenser 225 to ground at 226.

20 Figure 4 shows an alternative equipment for station B of Figure 1. The line 12 becomes 243. The busy signal 171 becomes 245 and 246. The printer and sender 148 and 149 become 234 and 25 244. The motor 146 becomes 227.

25 A motor-stopping pull-bar 228 is arranged to engage a pivoted bar 229 and also to close a switch 238. The motor-starting magnet 232 has an armature 242 which is at the same time a 30 latch for the bar 229. The bar 229 operates a set of contacts 231, 233, 235. The motor starting magnet 232 is connected to earth through the starting key or calling key, and it has the guard relay 237 of low resistance as compared with magnet 232. The relay 237 is normally free from ground connection but it may be connected to ground through the switch 238 or through its own armature contact.

35 The apparatus is shown in its non-operating 40 condition. The bar 229 is latched by the armature 242. The line wire 243 is connected through the contact 233 and through the magnet 232 and the calling key to ground. The printer 234 and sender 244 are open-circuit. The motor is open- 45 circuit. The relay 237 is open-circuit. The supervisory current through the central office relay 91 is flowing through the magnet 232 but is insufficient to operate the magnet.

50 In operation, should the switch 5 connect with the line 243, current of signaling value will flow through the magnet 232 and will energize the magnet to operate its armature 242 to release the pivoted bar 229. This will reverse the contacts 231, 233 and 235. The contact 231 will energize 55 the motor 227. The contact 235 will close, forming a path from the line wire 243 through the contact 235, printer magnet 234 and sender 244 to ground. The contact 233 will open, removing the line wire 243 from the magnet 232 and from the relay 237. Normal telegraphic signaling conditions thus are set up.

55 Should the operator at the apparatus of Figure 4 desire to call the central office to send a message, the starting key is operated briefly. This releases the supervisory relay 91 of Figure 1 and when the switch 15 of Figure 1 has connected the set 2 of Figure 1 to the line 12 which is the line 60 65 243, the action at Figure 4 will be the same as described above in response to switch 5.

70 When signaling is completed, the central office must release the line 243 but before doing so the operator at the central sends to the printer magnet 234 the predetermined code combination of signaling conditions which will control the print- 75

er to operate the motor-stopping pull-bar 228. The bar 228 operates, closes the switch 238, rocks the bar 229, reverses the contacts 231, 233, 235 and brings the bar 229 under the latch 242. The line 243 is removed from the printer magnet 234 and is connected through magnet 232 to earth, shunted by the relay 237 and switch 238 to earth. Relay 237 operates and closes its path through its own armature to earth. Magnet 232 does not control its armature because its winding is shunted by the comparatively low resistance of the relay 237. This condition continues as long as the full signal current continues. When the central office operator releases the line 12 and the current in the line is reduced to its supervisory intensity, the relay 237 will release its armature and the apparatus will be again in its non-operating condition as at first described.

As shown in Figure 1 the apparatus at the central station may also be restored to normal automatically in an interval of time. Details for restoring manually rather than automatically are illustrated in Figures 6 and 7. In Figure 6 the code transmitter and switching mechanism, motor and code transmitter receiver are all similar to that shown in Figure 1 and are accordingly labelled the same. The signaling line however, extending from the switch 29 is here shown connected to a key mechanism 260 comprising switches 261-264, a locking armature 265 and magnet 266. Normally the magnet 266 is connected to the line over the switch 261 in engagement with its contact. When switch 29 closes its contacts, a telegraph current is impressed across the line which energizes the magnet 266 to operate armature 265 releasing the switches controlled thereby. Switch 261 operates a make before break contact and signaling line is switched thereover from the magnet 266 to the printing apparatus receiver relay 18 and transmitter 19, and the test circuit is closed at switch 263. At the end of the signaling period the key 261 is operated by the central station operator to restore switches to the position shown, permitting the latch 265 to drop and engage them and hold them in their latched position.

In Figure 7 this automatic equipment is shown in connection with the telegraph equipment for receiving incoming signals. The equipment is identical with that shown in Figure 1 and the same figures are therefore employed. Switch 134 is shown connected through the switch 270 to relay 271 and thence to battery 272 and ground. The current flowing over conductor 121 is normally insufficient to operate relay 271. When a telegraph signal is received however, relay 271 energizes and moves its latch armature 273 to release the contacts of the switches 270, 274, and 275 and the signaling line 121 is switched from a connection with relay 271 to the receiving apparatus over the switch 275. At the end of the signaling period the switch 276 is operated and will restore the switches to the position shown.

It will be clear that following a selection of a substation, a start impulse may be transmitted from the central station which will start the apparatus at the outlying station into operation. A code for spacing impulses will then be received from the outlying station by means of which the phase and synchronisms of the two sets can be compared by the central station operator.

Although I have shown my invention as applied to a preferred embodiment, it will be clear that it may be practiced in many other forms and I do not intend to limit myself to the arrangements

shown but only insofar as set forth in the appended claims.

I claim:

1. In a telegraph system, a central station, a remote station, a telegraph set at said remote station comprising a telegraph transmitter and receiver magnet, a motor for operating said telegraph set, means for maintaining said motor normally in a non-operating condition, a telegraph set at said central station, automatic apparatus, and means at said remote station for operating said automatic apparatus to condition said remote and said central station set for intercommunication, said first mentioned means being controlled from said central station for starting said motor into operation and for simultaneously rendering said second mentioned means non-operative, said first mentioned means being also operative when said motor is in a non-operating condition for rendering said transmitter non-operative. 20

2. In a signaling system, a first station, remote stations, a plurality of signaling lines at said first station extending to said remote stations, a bank of lamps comprising a lamp individual to each of said signaling lines, automatic switching means for seizing one of said lines, the lamp individual to said line being automatically illuminated when said line is seized and means for varying the luminosity of said lamp to indicate which of said lines is seized. 30

3. In a telegraph switching system, a first station, a plurality of remote stations, signaling lines extending to each of said remote stations, a lamp at said first station individual to each of said lines, automatic switching means for seizing one of said lines, said lamps being illuminated as their associated lines are seized whereby a plurality of said lamps may be illuminated at any one time and means operative following the seizing of any one of said lines for varying the luminosity of the lamp individual thereto whereby indication is provided of the line seized. 35

4. In a telegraph switching equipment, a first station, a plurality of remote stations, signaling lines extending from said first station to said remote stations, a lamp individual to each of said lines, automatic equipment individual to each of said lines, the lamps individual thereto being illuminated as their associated lines are seized whereby a plurality of said lamps are illuminated 50 simultaneously and means whereby indications can be provided at any time of a signaling line seized. 45

5. In a telegraph system, a first station, a remote station, a telegraph set comprising a transmitter and a receiver, a motor therefor, said motor being energized while said receiver is stopped in a normally non-operating condition, automatic switching equipment, a signaling line connecting said set to said automatic switching equipment, a dial in said signaling line, means for operating said dial to open and close said line for transmitting codes of impulses to said automatic switching equipment, means for maintaining said receiver unoperated while said line is being opened by said dial. 60

6. In a telegraph system, a telegraph set comprising a transmitter and a receiver magnet, an automatic switching equipment, a signaling line connecting said switching equipment and said set, a dial in said signaling line, said telegraph receiver magnet being normally energized during a stop or non-operating period, means for operating said dial to transmit signals to said automatic switching equipment and means for retaining the 75

armature of said receiver magnet non-responsive to said signals.

7. In a telegraph system, a first station, a plurality of remote stations, signaling lines extending from said central station to each of said remote stations, automatic switching equipment, a plurality of receiver sets at said central station comprising transmitters and receiver magnets, a telegraph set at each of said remote stations each comprising a telegraph transmitter and receiver, means at said central station for operating said automatic switching equipment to seize one of said signaling lines, means responsive thereto for starting said transmitter and receiver at said remote station individual to said seized line into operation, means for maintaining the receiver magnet at said remote station energized following the starting of said receiver motor individual thereto into operation, means for maintaining the receiver magnet at said central station energized while said switching operations occur and means for connecting said telegraph sets in series with each other while retaining the printers unoperated.

- 25 8. In a telegraph system a central station comprising a first group of telegraph sets arranged for outgoing signals, a second group of telegraph sets for incoming signals, a plurality of outlying stations, signaling lines individual thereto, automatic switching equipment individual to said first group of sets for connecting said sets to any one of said signaling lines extending to said outlying stations and a second automatic switching equipment individual to each of said outlying stations controlled therefrom for automatically connecting the line from said outlying station to any one of said incoming sets.

- 40 9. In a telegraph system, a plurality of outlying stations, lines individual to each station, a central station, comprising a first group of telegraph sets arranged for outgoing signals, a second group of telegraph sets for incoming signals, automatic switching equipment individual to said first group of sets for connecting said sets to any one of said signaling lines extending to said outlying stations, a second automatic switching equipment individual to each of said outlying stations controlled therefrom for automatically connecting the line from said outlying stations to any 45 one of said incoming sets, and means operative for conditioning one of said sets for either outgoing or incoming messages.

- 50 10. In a telegraph system a central station comprising a plurality of groups of telegraph sets, a plurality of outlying stations, signaling lines individual to each of said outlying stations, automatic switching equipment connecting one group of said sets to said signaling lines, said automatic switching equipment being responsive to control from a central station, additional automatic switching equipment individual to each of said outlying stations and controlled therefrom for connecting said signaling lines from said outlying stations to any one of said other groups of said telegraph sets and means for connecting said one group of said sets to said additional automatic telegraph switching equipment.

- 70 11. In a telegraph system, a central station, a plurality of outlying stations, signaling lines connecting said central station with each of said outlying stations, means for automatically connecting said central station with each of said outlying stations, audible and visual signaling devices at each of said outlying stations, telegraph sets at each of said outlying stations normally

in non-operating condition, means at said central station for rendering said sets operative and for operating said audible and visual signaling devices, and means at said outlying stations operative an interval of time after signaling between stations has ceased for automatically rendering said telegraph sets thereat non-operative.

- 5 12. In a telegraph system, a central station comprising a plurality of telegraph sets, a plurality of outlying stations comprising telegraph sets, motors individual to each of said sets at said outlying stations and normally in a non-operating condition, means at each of said telegraph sets at said central station for starting the motor at any one of said outlying stations into 10 operation, means for communicating with said one outlying station, and means at said outlying station operative after an interval of time for rendering said motor thereat non-operative.

- 10 13. In a telegraph system, a station comprising a plurality of telegraph sets, a plurality of remote outlying stations each having a telegraph set, signaling lines connecting each of said outlying stations with said central station, automatic equipment controlled from said central station 20 for connecting any one of said central station sets with an outlying station, automatic switching equipment controlled from said outlying station for connecting said outlying station with said central station sets, and means at said central 25 station operative following any one of said connections whereby all signaling is controlled from said central station and is discontinued solely under control from said central station.

- 30 14. In a telegraph system, a station comprising a plurality of telegraph sets, a plurality of remote outlying stations each having a telegraph set, signaling lines connecting each of said outlying stations with said central station, automatic equipment controlled from said central station 35 for connecting any one of said central station sets with an outlying station, automatic switching equipment controlled from said outlying stations for connecting said outlying stations with said central station sets, means at said central station operative following connections whereby all 40 signaling is controlled from said central station and is discontinued solely under control of said central station, and signaling lamps for indicating with which of said outlying stations communication is taking place.

- 45 15. In a telegraph system, a central station, a plurality of outlying substations, signaling lines connecting said central station with each of said outlying stations, means for automatically connecting said central station with each of said outlying stations, audible and visual signaling devices at each of said outlying stations, a telegraph set at each of said outlying stations normally in a non-operating condition and means at said central station for rendering said set operative and for operating said audible and visual signaling devices.

- 55 16. In a telegraph system, a calling station, a called station, switching means under control 60 of said calling station for effecting connection with said called station, means solely controlled by said called station for releasing the connection thus established, and means including said switching means for transmitting code combinations of marking and spacing conditions between said calling and called station.

- 65 17. In a signaling system, a calling station, a called station, switching means controlled by said calling station for effecting connection with said 70

5 called station, means whereby said called station following said connections maintain sole control of said connection, and means including said switching means for transmitting code combinations of marking and spacing conditions between said calling and called station.

10 18. In a signaling system, a calling station, a plurality of called stations, means controlled by said calling station for selectively effecting connection with one of said called stations, means whereby said called station following said connection retains sole control of said connection, and means including said switching means for transmitting code combinations of marking and spacing conditions between said calling and called station.

15 19. In a telegraph system, a central station, a plurality of remote outlying stations each having a telegraph set, a signaling line connecting each 20 of said outlying stations with said central station, automatic equipment controlled from said central station for connecting said central station with one of said outlying stations, automatic switching equipment controlled from said outlying 25 stations for connecting said outlying stations with said central station and means at said central station operative following any one of said connections whereby said connection is solely under control from said central station.

30 20. In a telegraph system, a central station, a plurality of remote outlying stations, each having a telegraph set, a signaling line connecting each of said outlying stations with said central station, means controlled from any one of said 35 outlying stations for connecting said outlying station with said central station and means at said central station following said connections whereby said connection is under sole control from said central station.

35 21. In a telegraph system, a central station, a plurality of remote outlying stations, each having a telegraph set, a signaling line connecting each of said outlying stations with said central station, automatic switching equipment controlled from said outlying stations for connecting said outlying station with said central station and means at said central station following said connections whereby said connection is under sole control from said central station.

40 22. In a telegraph system, a central station, an outlying station, a signaling line connecting said outlying station with said central station, automatic equipment controlled from said central station for connecting said station with said outlying 45 station, automatic switching equipment controlled from said outlying station for connecting said outlying station with said central station and means at said central station operative following any one of said connections whereby said connection is maintained solely under control from said central station.

45 23. In a telegraph system, a central station, an outlying station, a signaling line connecting said stations, automatic switching equipment controlled from said outlying station for connecting said outlying station with said central station and means at said central station operative following said connection whereby said connection is maintained solely under control from said central station.

50 24. In a telegraph system, a plurality of outlying stations, a central station, a signaling line connecting said central station with each of said outlying stations, a plurality of telegraph receiving apparatus at said central station, means

5 whereby the first idle one of said central station's receiving apparatus is seized in response to an operation from said outlying stations therewith and means whereby the release of the seized apparatus is solely under control from said central station.

10 25. In a telegraph system, a central station having a plurality of printing apparatus thereat, a plurality of outlying stations, a signaling line extending from said central station to each of said outlying stations, automatic switching equipment at said central station, means controlled from said central station for operating said automatic switching equipment, means responsive to said automatic switching equipment for seizing one of said outgoing lines and means responsive to an operation at one of said outlying stations for connecting one of said central station apparatus to said outlying station signaling.

15 26. In a signaling system, a central station, a plurality of outlying stations, a plurality of apparatus units at said central station, a signaling line extending from said central station to each of said outlying stations and means whereby any one of said central station apparatus units may 20 be connected with an outgoing line to one of said outlying stations, either under control from said central station or from said outlying stations.

20 27. In a signaling system, a central station, a plurality of outlying stations, a plurality of apparatus units at said central station, a signaling line extending from said central station to each of said outlying stations and means whereby any one of said central station apparatus units may be connected with an outgoing line to one of said 25 outlying stations, either under control from said central station or from said outlying stations and means whereby following said connection said connection is maintained solely under control from said central station.

30 28. In a telegraph system, a first station, a remote station, a telegraph set comprising a transmitter and a telegraph receiver, automatic switching equipment, a signaling line connecting said set to said automatic switching equipment, a dial in said signaling line, said telegraph apparatus being normally disconnected from said signaling line, means to operate said dial to transmit code impulses over said line to operate said automatic switching equipment, and means 35 operative following the complete operation of said switching equipment to complete connections to said outlying stations for associating said printing apparatus with said signaling line.

40 29. In an automatic telegraph system, a central station, a plurality of apparatus thereat, an outlying station, a single signaling line connecting said stations, automatic switching equipment under control from said central station for seizing said signaling line and switching equipment 45 at said central station responsive to an operation from said outlying station over said signaling line for associating one of said central station apparatus with said signaling line.

45 30. In a signaling system, a central station, a plurality of outlying stations, a signaling line extending from said central to each of said stations, and automatic means whereby connections from said central to one of said outlying stations associated with one of said signaling lines may 50 be effected from either end automatically.

55 31. In a signaling system, a central station, a plurality of outlying stations, a signaling line extending from said central to each of said stations, an automatic means whereby connections 60

from said central to one of said outlying stations associated with one of said signaling lines may be effected from either end automatically, and means whereby following said connection, it is 5 maintained solely under control from said central station.

32. In a signaling system, a central station, a plurality of apparatus thereat, a plurality of outlying stations, a signaling line extending from 10 said central to each of said outlying stations, automatic switching equipment, means controlled from said central station for operating said automatic switching equipment to seize one of said signaling lines for connecting the central station apparatus with the apparatus at said outlying stations associated with said signaling line, and switching means at said central station responsive to an operation from an outlying station 15 over the signaling line associated therewith for connecting one of said central station apparatus with the signaling apparatus at said outlying station over said signaling line.

33. In a signaling system, a central station, a plurality of apparatus thereat, a plurality of outlying stations, a single signaling line extending from 20 said central to each of said outlying stations, automatic switching equipment, means controlled from said central station for operating said automatic switching equipment to seize one 25 of said signaling lines for connecting the central station apparatus with the apparatus at said outlying stations associated with said signaling line, and switching means at said central station responsive to an operation from an outlying station 30 over the signaling line associated therewith for connecting one of said central station apparatus with the signaling apparatus at said outlying station over said signaling line, and means whereby following said first-mentioned connection, said first-mentioned connection is 35 maintained solely under control from said central station.

34. In a signaling system, a central station, having a plurality of apparatus, a plurality of outlying stations each having apparatus, a signaling line individual to each of said outlying stations extending from said central station to its individual outlying station, switching equipment at said central station, means controlled 40 from said central station to operate said switching equipment to associate one of said apparatus thereat with a predetermined one of said signaling lines, means responsive to their association for associating the apparatus unit at the outlying station with said signaling line, a second switching equipment at said central station, means controlled from any one of said outlying stations for operating said second switching equipment and means responsive to the operation 45 of said second switching equipment for associating one of said central station apparatus with said signaling line and simultaneously associating said outlying station apparatus with said signaling line.

35. In a signaling system, a central station, having a plurality of apparatus, a plurality of outlying stations, having apparatus, a single signaling line individual to each of said outlying stations extending from said central station to its individual outlying station, switching equipment at said central station, means controlled from said central station to operate said switching equipment to associate one of said apparatus with a predetermined one of said signaling lines, 50 means responsive to the last mentioned means for

associating the apparatus at the outlying station with said signaling line, a second switching equipment at said central station, means controlled from said outlying station for operating said second switching equipment, means responsive to the operation of said second switching equipment for associating one of said central station apparatus with said signaling line and simultaneously associating said outlying station apparatus with said signaling line and means whereby following said connections said connections are maintained solely under control from said central station.

36. In a signaling system, a central station; a local circuit thereat; printing apparatus normally connected in said local circuit, an outlying station; a signaling line connecting said stations, printing apparatus at said outlying station normally disconnected from said signaling line, automatic switching equipment, means controlled from said central station for operating said automatic switching equipment, means responsive to said automatic switching equipment operation for seizing said outlying station, and means responsive to the seizing of said outlying station for connecting the printing apparatus thereto said signaling line and for disconnecting the apparatus at said central station from its local circuit and connecting it to said signaling line.

37. In a telegraph system, a central station, an outlying station, a local circuit at said central station, a signaling line connecting said stations, telegraph apparatus at each of said stations, said telegraph apparatus at said central station being normally connected in said local circuit, switching mechanism, means controlled by either of said stations for operating said switching mechanism for connecting said central station with said outlying station, and means operative following said connection for disconnecting said telegraph apparatus at said central station from said local circuit and for connecting said telegraph apparatus at said central and said outlying station to said signaling line.

38. In a telegraph system a central station, an outlying station, a closed local circuit at said central station, a signaling line connecting said stations, telegraph apparatus at each of said stations, said telegraph apparatus at said central station being normally connected in said local circuit, switching mechanism, means controlled by either of said stations for operating said switching mechanism for connecting said central station with said outlying station, and means operative following said connection for disconnecting said telegraph apparatus at said central station from said local circuit and for connecting said telegraph apparatus at each of said stations to said signaling line, said central station telegraph apparatus being normally in closed circuit condition and maintained in the same condition while switched from the said local circuit to said signaling line.

39. In a telegraph system, a central station, an outlying station, a local circuit at said central station, a signaling line connecting said stations, telegraph apparatus at each of said stations, said central station telegraph apparatus being normally connected in said local circuit thereto; switching mechanism, means controlled by either of said stations for operating said switching mechanism for connecting said central station with said outlying station, means operative following said connection for disconnecting said

- telegraph apparatus at said central station from said local circuit and for connecting said telegraph apparatus at each of said stations to said signaling line, said central station telegraph apparatus being maintained in the same condition as obtained when connected in the local circuit while being switched to said signaling line.
40. In a telegraph system, a central station, an outlying station, a local circuit at said central station, a signaling line connecting said stations, telegraph apparatus at each of said stations, said central station telegraph apparatus being normally connected to said local circuit, switching mechanism, means controlled by either of said stations for operating said switching mechanism to connect said central station with said outlying station, means operative following said connection for disconnecting said telegraph apparatus at said central station from said local circuit, and for connecting said telegraph apparatus at each of said stations to said signaling line, and a make before break switch for maintaining said central station telegraph apparatus in the same condition as obtained when it is connected in said local circuit during switching.
41. In a telegraph system, a central station having a plurality of telegraph apparatus, a plurality of outlying stations, a plurality of signaling lines connecting said stations, switching equipment, means controlled from said central station for operating said switching equipment to connect one of said signaling lines with one of said central station apparatus for communication with one of said outlying stations, second switching equipment, and means controlled from any one of said outlying stations for associating any one of said central station apparatus with the signaling line to said outlying station for permitting communication therebetween.
- 40 42. In a telegraph system, a central station, a remote station, a line circuit connecting said stations, a motor at said remote station, a receiver and a transmitter at said remote station, said transmitter being operable to send telegraphic signals by opening said line circuit in code manner, switching apparatus at said central station connected to said line circuit and responsive to a brief opening of said line circuit, and means for starting and stopping said motor, said means being operative to render said transmitter incapable of opening said line circuit when in condition to stop said motor.
43. In a telegraph system, a central station, a remote station, a line circuit connecting said stations, a motor at said remote station, a receiver and a transmitter at said remote station, switching apparatus at said central station connected to said line circuit and responsive to a brief opening of said line circuit, a calling key at said remote station adapted to open said line briefly to control said automatic apparatus, and means for starting and stopping said motor, said means being operative to render said calling key ineffective when in condition to energize said motor to run.
44. In a signaling system, a plurality of signaling lines, busy indicators, one for each of said lines, means to engage a line for signaling and for displaying the indicator thereof; and further means for controlling the indicator variably.
45. In a signaling system, a plurality of signaling lines, a busy indicator for each of said lines, a pilot conductor connected to said busy indicator over which said busy indicator is operated, automatic switches to engage a line for signal-
- ing and for operating said indicator, and means to vary the operation of said indicator by varying the current in said pilot conductor.
46. In a signaling system, a signaling line, a pilot conductor for said line, a busy-guard connection for said conductor, an indicator for said conductor operated by said connection, and means for operating said indicator variably while maintaining said busy-guard connection continuously effective.
47. In a signaling system, an automatic switch, a telegraph set, a source of current, a closed circuit including said switch, said set and said source and having a continuous current through said set and through said switch, and means for interrupting the current through said switch while maintaining the current continuously through said set.
48. In a signaling system, an automatic switch, a telegraph set, a source of current, a closed circuit including said switch, said set and said source and having a continuous current through said set and through said switch, a first dial-operated switch which deprives said automatic switch of current in a variable code manner, and a second dial-operated switch which provides current for said set in a continuous manner.
49. In a signaling system, an automatic switch, a telegraph set, a source of current, a closed circuit including said switch, said set and said source and having a continuous current through said set and through said switch, and a dial-operated mechanism adapted to operate said switch independently of said set.
50. In a telegraph switching system, a telegraph set, a local circuit for said set, line circuits for said set, switches for transferring said set from its local circuit to a line circuit, and means for maintaining said set unoperated during the transition from circuit to circuit.
51. In a telegraph switching system, a telegraph set, a local circuit for said set, line circuits for said set, switches for transferring said set from its local circuit to a line circuit, and make-before-break-contacts for maintaining said set unoperated during the transition from circuit to circuit.
52. In a signaling system, a central station, a plurality of sub-stations, a single circuit connecting a substation to the central station, a concentration system located at the central station comprising a plurality of recorders, a message distribution system located at the central station comprising a plurality of transmitters, means at each central station transmitter to control said distribution system, and means at each substation to control said concentration system; both of said systems being operable over said circuit.
53. In a signaling system, a first station, an outlying station, signaling apparatus at each station, selector mechanism at said first station, and means whereby said selector mechanism at said first station may be variably controlled from either of said stations for effecting a connection between the signaling apparatus at said stations.
54. In a signaling system, a message relay station, a plurality of remote stations, a plurality of outgoing signaling sets at said relay station, a plurality of storing signaling sets at said relay station, signaling apparatus at each of said remote stations, switching mechanism at said relay station, means whereby said switching mechanism may be variably controlled at said relay station for effecting a connection between one of said outgoing signaling sets and the apparatus

5 at one of said remote stations for transmission of a message stored on one of said storing signaling sets, and means whereby said switching mechanism may be controlled from any one of said 5 remote stations for effecting a connection between the apparatus of said remote station and one of said storing signaling sets at said relay station.

55. In a signaling system, a relay station, a 10 plurality of outlying stations, a plurality of message storing and transmitting sets at said relay station, signaling apparatus at each of said outlying stations, switching mechanism at said relay station associated with said message storing 15 sets, other switching mechanism at said relay station associated with said transmitting sets, means whereby said transmitting switching apparatus may be controlled from said relay station for effecting a connection between one of 20 said transmitting sets and the apparatus at any one of said outlying stations for transmission of a message stored on one of said storing sets, and means whereby said storing switching apparatus may be controlled from any of said outlying 25 stations for effecting a connection between the apparatus thereat and one of said storing sets at said relay station.

56. In a signaling system, a first station, a plurality of outlying stations, a plurality of incoming and outgoing signaling sets at said first station, signaling apparatus at each of said outlying stations, switching mechanism at said first station associated with said outgoing sets, other switching mechanism at said first station associated with said incoming sets, means whereby said outgoing switching apparatus may be controlled from said first station for effecting a connection between one of said outgoing signaling sets and one of said outlying stations, means 40 whereby said incoming switching apparatus at said first station may be controlled from any of said outlying stations for effecting a connection between said apparatus thereat and one of said incoming signaling sets at said first station, and 45 a single signaling line in which the apparatus at each of said outlying stations is connected.

57. In a signaling system, a central station, a plurality of outlying stations, a plurality of incoming and outgoing signaling sets at said central station, signaling apparatus at each of said outlying stations, switching mechanism at said central station associated with said outgoing sets, other switching mechanism at said central station associated with said incoming sets, means 55 whereby said outgoing switching apparatus may be controlled from said central station for effecting a connection between one of said outgoing signaling sets and one of said outlying stations, means whereby said incoming switching apparatus at said central station may be controlled from any of said outlying stations for effecting a connection between said apparatus thereat and one of said incoming signaling sets at said central station, single individual signal- 60 lines connecting said central and outgoing stations, means whereby all of said operations are effected over said single signaling circuits, and means including said single signaling circuits for communicating between the connected signaling 65 apparatus and signaling sets.

58. In a signaling system, a central station, a plurality of outlying stations, a plurality of receiving message storing and transmitting signaling sets at said central station, signaling apparatus at each of said outlying stations, switch- 70

ing mechanism at said central station associated with said transmitting sets, other switching mechanism at said central station associated with said receiving sets, means whereby said transmitting switching apparatus may be controlled at said central station to effect a connection between one of said transmitting sets and one of said outlying stations, for transmission of a message stored on one of said receiving sets, means whereby said receiving switching apparatus at said central station may be controlled from any of said outlying stations for effecting a connection to one of said receiving sets at said central station, a single signaling line connecting each of said remote stations to said central station, means whereby all of said operations between the outlying stations and said central station are effected over said single signaling circuits, and a signaling device at said central station individual to each of said signaling lines 20 for indicating a busy condition of said lines.

59. In a signaling system, a relay station, a plurality of outlying stations, a plurality of incoming and outgoing signaling sets at said relay station, signaling apparatus at each of said outlying stations, switching mechanism at said relay station associated with said outgoing sets, other switching mechanism at said relay station associated with said incoming sets, means whereby said outgoing switching apparatus may be controlled from said relay station for effecting a connection between one of said outgoing signaling sets and one of said outlying stations, means whereby said incoming switching apparatus at said relay station may be controlled from any of said outlying stations for effecting a connection between the apparatus thereat and one of said incoming signaling sets at said relay station, a single signaling line connecting each of said outlying stations to said relay station, means whereby all of said operations between said relay station and said outlying stations are effected over said single signaling circuit, means including said single signaling circuits for communicating between signaling apparatus and sets connected thereto, a signaling device at said relay station individual to each of said signaling lines for indicating a busy condition of said lines, and means whereby said signaling devices may be variably operated from said relay station incoming and 50 outgoing signaling sets for indicating to an attendant, the line to which the relay station apparatus is connected.

60. In a signaling system, a relay station, a plurality of outlying stations, a plurality of incoming and outgoing signaling sets at said relay station, a signaling set at each of said outlying stations, switching mechanism at said relay station associated with said outgoing sets, other switching mechanism at said relay station associated with said incoming sets, means whereby said outgoing switching apparatus may be controlled from said relay station for effecting a connection between one of said outgoing signaling sets and one of said outlying stations, means whereby said incoming switching apparatus at said relay station may be controlled from any of said outlying stations for effecting a connection between the set thereat and one of said incoming signaling sets at said relay station, a normally non-operating motor for each of said outlying signaling sets, and means responsive to a connection between any of said signaling sets for starting the associated non-operating motors into operation.

61. In a signaling system, a relay station, a plurality of outlying stations, a plurality of incoming and outgoing signaling sets at said relay station, a signaling set at each of said outlying stations, switching mechanism at said relay station associated with said outgoing sets, other switching mechanism at said relay station associated with said incoming sets, means whereby said outgoing switching apparatus may be controlled from said relay station for effecting a connection between one of said outgoing signaling sets and a set at one of said outlying stations, means whereby said incoming switching apparatus may be controlled from any of said outlying stations for effecting a connection between the set thereat and one of said incoming signaling sets at said relay station, a normally non-operating motor for each of said outlying signaling sets, means responsive to a connection effected between any of said signaling sets for starting the associated non-operating motors into operation, and means whereby an attendant at said relay station retains full control of the signaling circuit following the interconnection of any pair of said sets through said switching mechanism irrespective of the origin of the connection.

62. In a signaling system, a central station, a plurality of outlying stations, a plurality of incoming and outgoing signaling sets at said central station, a signaling set at each of said outlying stations, switching mechanism at said central station associated with said outgoing sets, other switching mechanism at said central station associated with said incoming sets, means whereby said outgoing switching apparatus may be controlled from said central station for effecting a connection between one of said outgoing signaling sets and the set at one of said outlying stations, means whereby said incoming switching apparatus at said relay station may be controlled from any of said outlying stations for effecting a connection between the set thereat and one of said incoming signaling sets at said central station, a normally non-operating motor for each of said outlying sets, means responsive to a connection effected between any pair of said sets for starting the associated non-operating motors into operation, means whereby an operator at said central station retains full control of the signaling circuit following the interconnection of any pair of said sets through said switching mechanism irrespective of the origin of the connection, and means for transmitting a special calling signal from said central station to a connected outlying station.

63. In a signaling system, a concentration station, a plurality of substations, telegraph apparatus and a motor at each substation, a searching switch at the concentration station, a plurality of printing telegraph apparatus connected to the searching switch, means at a substation for starting the searching switch into operation, and means operated when the searching switch has seized a receiver to start the motor at the substation.

64. In a signaling system, a concentration station, a plurality of substations, a searching switch at the concentration station, a plurality of printing telegraph apparatus connected to the searching switch, means at a substation to start the searching switch into operation to seize one of said apparatus, and means operated when a telegraph apparatus has been seized to

indicate at the substation that the apparatus has been seized.

65. In a signaling system, a calling station, a non-operating motor at said calling station, a called station, circuit controlling apparatus at a point intermediate of said calling and called stations, and circuits and relays for starting said motor, said circuits being controlled from said called station through said apparatus to said calling station.

66. In an automatic switching system, a central office, a searching switch, a calling station served by said switch, a plurality of service circuits which said switch engages in succession, a further circuit engaged by said switch after said switch has engaged successively said service circuits, said further circuit containing an audible signal device at said calling station and a source of power at said central office, and means for stopping said switch briefly in engagement with said further circuit and for then restoring said switch to normal.

67. In a signaling system, a first station, a second station, a normally closed line circuit connecting said first station and said second station, a normally energized relay in said line circuit at said first station, means in said line circuit at said second station for opening said line circuit to de-energize said relay, means including contact points of said relay for eliminating said relay from said line circuit when said relay de-energizes and motor mechanism rendered operative by said relay while said relay is deenergized.

68. In a signaling system, a first station, a second station, a line wire, a normally closed line circuit connecting said first station and said second station, a normally energized relay in said line circuit at said first station, means in said line circuit at said second station for opening said line circuit to de-energize said relay, a motor mechanism at said first station, means including contact points of said relay for eliminating said relay from said line circuit when said relay de-energizes, and further means including further contact points of said relay for conditioning said motor mechanism to operate while said relay remains deenergized.

69. In a telegraph system, telegraph sets each having a lamp associated therewith, another telegraph set having a key associated therewith, said lamps being grouped adjacent to said key, and switching means to connect one of said sets to said other set and to connect the associated lamp to the associated key whereby said connected key may control said connected lamp to identify said connected one of said sets.

70. In a telegraph system, a first station, a plurality of second stations, signaling lines connecting said first station with each of said second stations, a plurality of telegraph receivers at said first station, means for originating calls at said second stations, and means at said first station for invariably switching incoming calls originating at said second stations to predetermined ones of said first station receivers if said predetermined receivers are idle when said messages are received.

71. In a telegraph system, including lines extending from a plurality of outlying telegraph stations to a central receiving station, transmitting apparatus at said outlying stations for initiating calls, a plurality of telegraph receivers at said central receiving station arranged in a predetermined sequence, and means for invari-

ably assigning incoming calls to the lowest numbered idle receiver.

72. In a telegraph system including lines extending from a plurality of outlying stations to a central receiving station, transmitting apparatus at said outlying station for initiating calls, a plurality of receivers at said central receiving station arranged in a predetermined sequence, means for invariably assigning incoming calls to the lowest numbered idle receiver, and means whereby any one of said receivers may be rendered non-operative to receive any incoming signals.

73. In a telegraphic switching system, a switch-board having a number of telegraphic call receiving sets arranged in a predetermined sequence, in combination with means including circuit connections whereby an incoming telegraphic call will be switched to the lowest numbered idle telegraphic call receiving set and whereby if a still lower numbered telegraphic call receiving set becomes idle before an incoming telegraphic call is initiated said incoming telegraphic call will be switched to said still lower numbered telegraphic call receiving set.

74. In a signaling system, a central station, central telegraph apparatus, a substation, substation telegraph apparatus, a line connecting said stations, a relay at said central station controlling the connection of said telegraph apparatus into operative relation, switching apparatus at said central station for selecting the central telegraph apparatus in response to a calling operation performed at the substation, and a circuit arrangement wherein said relay which sets the selected apparatus at the central station into operation is energized throughout the call, the energizing circuit being broken by the apparatus at the central station on completion of the call.

75. In a signaling system, a substation, a central station, a connecting relay at said central station operated in the action of said substation calling said central station, a holding circuit for said relay, and means solely operable at the central station for releasing said relay.

76. In a telegraph system, a first station, a second station, a line circuit connecting said stations, a motor at said second station, a receiver and transmitter at said second station, and a transmitter being operable to send telegraphic signals by opening said line circuit in code manner, and means for starting and stopping said motor, said means being operative also to render said transmitter incapable of opening said line when in condition to stop said motor.

77. In a telegraph system, a telegraph receiver, a telegraph transmitter, a motor for driving said receiver and transmitter, control mechanism for stopping and starting said motor, and an electrical contact in said control mechanism for disabling said transmitter.

78. In a telegraph system, a telegraph receiver, a motor for driving said receiver, electrical signal transmitting contacts, control mechanism for starting and stopping said motor, and an electrical contact in said control mechanism for short-circuiting said transmitting contacts.

79. In a telegraph system, a telegraph receiver, a motor for driving said receiver, a line circuit, electrical signal transmitting contacts for opening and closing said line circuit in code manner, control mechanism for starting and stopping said motor and an electrical contact in said control mechanism for short-circuiting said transmitting contacts.

80. In a telegraph system, a first station, a second station, a line connecting said stations, a receiver and transmitter at said second station, a motor at said second station for driving said receiver and transmitter, a key at said second station for opening said line circuit, and control means for starting and stopping said motor, said means being effective to render said key ineffective when said means is in condition to control said motor to run.

81. In a telegraph system, a first station, a second station, a line circuit connecting said stations, a receiver and transmitter at said second station, said transmitter being adapted to transmit telegraph signals by opening said line circuit in a code manner, a motor for driving said transmitter, a key at said second station for opening said line circuit, mechanism responsive to said key whereby in response to the opening of said line circuit by said key said motor will be started, thereby rendering said transmitter effective, and electrical contacts in said mechanism for preventing said key from opening said line circuit when said transmitter is effective to open said line circuit.

82. In a telegraph system, a first station, a remote station, a telegraph set at said remote station, a motor at said remote station for operating said set, electrical contacts normally open for maintaining said motor normally in non-operating condition, an electromagnet at said remote station responsive to current from said first station, said magnet controlling said contacts, and further contacts controlled by said magnet for rendering said magnet unresponsive.

83. In a telegraph system, a first station, a remote station, a telegraph set at said remote station, a motor at said remote station for operating said set, electrical contacts normally open for maintaining said motor normally in non-operating condition, a line circuit connecting said first station and said remote station, an electromagnet in said line circuit at said remote station responsive to current in said line circuit from said first station, said magnet controlling said contacts, and further contacts controlled by said magnet for rendering said magnet unresponsive to currents in said line circuit.

84. In a telegraph system, a first station, a remote station, a telegraph set at said remote station, a motor at said remote station for operating said set, electrical contacts normally open for maintaining said motor normally in non-operating condition, an electromagnet at said remote station responsive to current from said first station, said magnet controlling said contacts, further contacts controlled by said magnet for rendering said magnet unresponsive, and further means at said remote station for rendering said magnet again responsive to current from said first station.

85. In a telegraph system, a central station, a remote station, a telegraph set at said remote station, a motor for operating said telegraph set, means for maintaining said motor normally in a non-operating condition, and further means at said remote station controlled from said central station for starting said motor thereat into operation and for simultaneously rendering said further means non-responsive.

86. In a printing telegraph exchange system, a plurality of customers' stations, a central station, a normally unoperated line relay and a normally unoperated cut-off relay at said central

station individual to each of said customers' stations, a single line circuit between each of said customers' stations and said central station, means for operating both said line relay and said 5 cut-off relay when one of said customers' stations is calling, and means for operating said cut-off relay alone when one of said customers' stations is being called.

87. In a printing telegraph exchange system, 10 a customer's station, a central station, a receiving printer, a sending printer, incoming and outgoing switches at said central station, a single line between said customer's station and said central station, means for connecting said customer's station over said line and through said incoming switches to said receiving printer, and means for connecting said sending printer through said outgoing switches and over said line to said customer's station.

88. In a printing telegraph exchange system, 20 a customer's station, a central station, a receiving printer at said central station, a communication circuit between said customer's station and said printer, an independent release circuit for 25 maintaining said communication circuit at said central station, and means under control of the operator of said printer for breaking said release circuit and thereby disestablishing said communication circuit.

89. In a printing telegraph exchange system, 30 a customer's station, a central station, an automatically operative switch and a cut-off relay at said central station, a line extending from said customer's station to said switch, another circuit 35 extending from said cut-off relay to said switch, means for operating said switch to extend said line to said central station, a normally unoperated relay at said central station, means responsive to the operation of said switch for 40 operating said relay and means responsive to operation of said relay for extending said other circuit to ground associated with said relay.

90. In a printing telegraph exchange system, 45 a customer's station, a central station, a cut-off relay, an automatic switch, a receiving printer

set and a relay at said central station, means for extending a release circuit from said cut-off relay to said automatic switch and means for operating said switch, under control of said customer's station, means responsive to the operation of 5 said switch for energizing said relay, and means responsive to the operation of said relay for extending said release circuit to said receiving printer set.

91. In a printing telegraph exchange system, 10 a central station, a printer at said station, a closed local circuit through said printer, a customer's station, automatic means for establishing connection between said customer's station and said central station printer, and means responsive to said interconnection for breaking 15 said closed local circuit through said printer.

92. In a printing telegraph exchange system, 20 a plurality of customer stations, printing telegraph equipment and driving means therefor at each of said stations, a central station, printing telegraph equipment and driving means therefor at said central station, a single wire closed circuit between said customer stations and said central station, automatic means for interconnecting the printing telegraph equipment at said customer station and said central station, and means responsive to said interconnection for 25 starting the driving means at said customer station.

93. A telegraph signaling system comprising a plurality of outlying stations each station being provided with telegraphic instrumentalities operated by a motor, a central station comprising a plurality of receivers connectible with said instrumentalities over circuits, selecting means 35 controllable from any one of said outlying stations for selecting an idle one of said receivers whenever any of said receivers is idle and establishing a connection therebetween and said instrumentalities, and means responsive to the establishment of such connection for starting the motor at the station.

EDWARD E. KLEINSCHMIDT. 45
